UNITED STATES PATENT OFFICE

ANDREW EZGETA AND CHARLES D. FLAMM, OF CHICAGO, ILLINOIS, ASSIGNEES OF FIFTY-FIVE PER CENT TO SAID EZGETA AND FORTY-FIVE PER CENT TO SAID FLAMM

WINDOW CONSTRUCTION

Application filed August 8, 1928. Serial No. 298,222.

This invention relates to improvements in window construction, and particularly to windows of the sliding sash type.

One object of the present invention is to provide a construction and arrangement whereby the upper and lower sashes may be raised and lowered in the same manner as ordinary window sashes, and wherein the construction and arrangement is such as to enable either or both of the sashes to be tilted or swung inwardly to positions at various degrees of angularity with respect to the window casing or frame in a manner to provide convenient access to the outer side of the window glass for the purpose of washing or the like.

Another object of the invention is to provide a novel construction and arrangement wherein the ordinary counterweights and sash chains or cords are employed for supporting the sashes in various tilted positions of angularity with respect to the window frame in which the sashes are adjustably mounted.

Another object of the invention is to provide novel and suitably positioned fulcrums around which the upper and lower sashes may be tilted, and supported by the sash chains at various angles with respect to the window frame.

Another object of the invention is to provide a novel form of metallic weather striping comprising a feature of the present invention, and particularly adaptable for use in connection with windows of the character disclosed in the illustrative embodiment shown in the drawings.

A further object of the invention is to provide a novel form of finger or bolt construction comprising a portion of the sash guiding means, whereby the bolt may be conveniently manipulated to various positions and readily secured in such positions in a manner to prevent accidental displacement therefrom.

A still further object of the invention is to improve devices of this character in sundry details hereinafter described and particularly pointed out in the appended claims.

One embodiment of the invention is shown

for illustrative purposes in the accompanying drawings, in which

Fig. 1 is an inside view of a window casing and window sashes mounted therein embodying features of the invention;

Fig. 2 is a vertical sectional elevational view taken substantially as indicated by the line 2—2 of Fig. 1 showing the window sashes in changed or tilted position;

Fig. 3 is an enlarged sectional plan view taken substantially as indicated by the line 3—3 of Fig. 1;

Fig. 4 is an enlarged elevational face view of one of the side members of the window frame illustrating the arrangement of the guiding slots formed therein and the notches formed adjacent the slots for providing fulcrums around which the window sashes may be tilted;

Fig. 5 is an enlarged sectional plan view of a portion of Fig. 3;

Fig. 6 is an enlarged fragmentary perspective view of a portion of the lower corner of one of the window sashes;

Fig. 7 is an enlarged fragmentary perspective view of a portion of one of the metal weather strips forming one of the features of the present invention;

Fig. 8 is an enlarged elevational face view of the novel finger or bolt mechanism forming a part of the sash guiding means and a feature of the present invention;

Fig. 9 is a sectional elevational view of the bolt mechanism taken substantially as indicated by the line 9—9 of Fig. 8; and

Fig. 10 is a sectional plan view of the parts shown in Fig. 8, the view being taken substantially as indicated by the line 10—10 thereof.

In the illustrative embodiment of the invention, a window frame or casing, indicated as a whole by the numeral 11, is provided with upper and lower window sashes 12 and 13, respectively, to which are attached one end of the usual sash cords or chains 14 and 15 adapted to be trained over pulleys 16 and 17 rotatably mounted in outer and inner pulley stiles 18 and 19, respectively, and having suspended from their opposite ends the usual counterweights 20 and 21, the former being

connected and operable to counterbalance the upper sash 12, and the latter, to counterbalance the lower sash 13.

For slidably mounting the sashes 12 and 13 in the frame 11, the pulley stiles 18 and 19 are provided with vertically disposed slots 22 and 23, respectively, and the sashes 12 and 13 are provided adjacent their lower edges with trunnions 24 and 25 adapted to engage the slots 22 and 23 of the frame. Suitably positioned in the side frame members of the sashes 12 and 13, adjacent the upper portions thereof, are bolts or fingers 26 slidably mounted in frame members 27 and adapted to be projected into sliding engagement with the slots 22 and 23 as indicated by full lines in Figs. 3 and 5 and by dotted lines in Fig. 10. It will be observed that by such an arrangement of the trunnions 24 and 25 and bolts 26 in the slots 22 and 23, the sashes 12 and 13 may be raised and lowered in the frame 11, as is customary in the ordinary window construction, and that the engagement of the trunnions and bolts with the slots prevents any lateral movement of the sashes with respect to the frame, notwithstanding the fact that no guide strips are provided adjacent the inner face of the sashes as is the usual practice in ordinary window construction.

For adjusting the bolts 26 into and out of engagement with the slots 22 and 23, the bolts are provided with screw threaded apertures 28 adapted to receive the threaded shank portions 29 of finger grip members 30 positioned outside of the frame member 27 and conveniently accessible for adjustment therein.

It will be observed by reference to Figs. 9 and 10 that by turning the member 30 counterclockwise, the bolt and finger grip member may be moved from the full line position to the dotted line position shown in Fig. 10, and by rotating the member 30 in a clockwise direction, the shoulder 31 on the member 30 will be forced snugly against the outer face of the frame member 27 in a manner to frictionally secure the bolt in adjusted position, either in or out of engagement with the slots 22 and 23 of the stiles 18 and 19.

This type of bolt construction is most desirable in a window structure of the character described as it provides conveniently actuated means for positively securing the bolts in operative position in the slots in a manner to prevent accidental displacement therefrom and insure efficient operation of the device.

For providing convenient access to the outer face of the window sashes 12 and 13, the bolts 26 are withdrawn from engagement with the slots 22 and 23, and the sashes moved upwardly in the frame or casing 11 until the trunnions 24 and 25 may be positioned in notches 32 and 33 formed adjacent

to and communicating with the slots 22 and 23, respectively, intermediate their end portions, thereby providing fulcrums about which the sashes 12 and 13 may be tilted inwardly at various angles with respect to the window frame 11, for example, to the positions shown in Fig. 2, in which positions the upper or free end portions of the sashes 12 and 13 are supported by means of the sash chains 14 and 15, the sash weights 20 and 21 serving to counterbalance the weight of the sashes in their tilted or adjusted positions.

By connecting the sash chains 14 and 15 to the side frame members of the sashes 12 and 13 intermediate their upper and lower end portions in a manner to support the upper end portions of the sashes when in tilted position, suitable provision is made for permitting the tilting of the sashes about their fulcrums without interference by the sash chains, and for this purpose the outer longitudinal vertical edges of the side frame members of the sashes 12 and 13 are cut away down to the point of attachment of the sash chains 14 and 15, as indicated at 34 in Figs. 1, 3 and 5 to provide ample space between the window frame 11 and adjacent portions of the window sashes for the passage of the sash chains 14 and 15 as the sashes are swung inwardly to their tilted positions.

For suitably weather-stripping windows of the character described, the pulley stiles 18 and 19 are provided with wear plates 35, and between the said plates and the stiles 18 and 19 are secured, by means of screws 36, the flanges or base portions 37 of resilient metal weather strips 38, the yielding portions 39 of which are adapted to be positioned between the outer face of the lower sash 13 and the pulley stiles 18, and between the outer face of the upper sash 12 and the weather-board 40. Thus, it will be observed that when the sashes 12 and 13 are in their normal slideable position, as shown in Figs. 1, 3 and 5, the free edges of the portions 39 of the weather strips 38 will yieldingly engage the outer faces of the sashes and provide a weather-tight connection between the frame 11 and the sashes 12 and 13.

It will be observed from the foregoing description that the present invention provides a novel type of window construction wherein the sashes 12 and 13 are slidably and tiltably mounted, and wherein the sash chains or cords 14 and 15 and counterweights 20 and 21 serve, not only to support and counterbalance the weight of the sashes when in their normal or slideable position, but also to support the sashes when tilted at various angles with respect to the frame.

Furthermore, the present invention provides a novel type of weather stripping particularly adaptable to window construction of the character described, and also an efficient and conveniently actuated bolt mecha-

nism capable of being secured in operative position and also out of operative position to prevent marring of the window frame in the event that the sashes, for any reason, should be moved from their desired tilted position to a point where the counterweights would act to suddenly draw the window sashes into alignment with the frame.

Obviously, the present invention is not limited to the precise construction and arrangement shown and described, as the same may be variously modified. Moreover, all the features of the invention need not be used conjointly as the same may be used to advantage in variously different combinations and sub-combinations.

What we claim is new and desire to secure by Letters Patent is:

1. In a window structure, the combination of a frame having a pair of vertical stiles spaced apart and provided on their co-operating inner faces with vertically disposed slots, a window sash mounted in a manner to operate between said stiles and capable of being tilted at an angle with respect to said stiles, a pair of trunnions secured to the vertical sides of the window sash adjacent the lower end thereof and being adapted to enter the vertical slots in said stiles in a manner to be guided therein, the said stiles each being provided with notches formed therein adjacent said vertical slots and communicating therewith, said notches being adapted to receive and support said trunnions in a manner to provide fulcrums about which said sash may be tilted, a pair of flexible members, one of each being secured to the vertical sides of the sash at points sufficiently near the upper end thereof to adequately support the sash when in tilted position on said fulcrums, anti-friction rollers in said stiles adjacent the upper ends thereof over which said flexible members are threaded, and weights for counterbalancing said sash secured to the free ends of said flexible members on the opposite sides of said anti-friction rollers from said sash.

2. In a window structure, the combination of a frame having a pair of vertical stiles spaced apart and provided on their co-operating inner faces with vertically disposed slots, a window sash mounted in a manner to operate between said stiles and capable of being tilted at an angle with respect to said stiles, a pair of trunnions secured to the vertical sides of the window sash adjacent the lower end thereof and being adapted to enter the vertical slots in said stiles in a manner to be guided therein, the said stiles each being provided with notches formed therein adjacent said vertical slots and communicating therewith, said notches being adapted to receive and support said trunnions in a manner to provide fulcrums about which said sash may be tilted, a pair of flexible members, one of

each being secured to the vertical sides of the sash at points sufficiently near the upper end thereof to adequately support the sash when in tilted position on said fulcrums, said flexible members being adapted to be deflected out of the plane of the said stiles when the sash is tilted on the said fulcrums, anti-friction rollers in said stiles adjacent the upper ends thereof over which said flexible members are threaded, and weights for counterbalancing said sash secured to the free ends of said flexible members on the opposite sides of said anti-friction rollers from said sash.

3. In a window structure, the combination of a frame having two pairs of vertical stiles adjacent but offset from each other and spaced apart and provided on their co-operating inner faces with vertically disposed slots, one of the pairs of vertical stiles being adapted to support an upper window sash, the other pair of said vertical stiles being spaced apart a distance slightly greater than the said pair of stiles supporting the upper window sash, upper and lower window sashes mounted to reciprocate between the respective pairs of stiles and each capable of being tilted at an angle with respect to said stiles, a pair of trunnions secured to the vertical sides of each window sash, there being one trunnion each of the respective sides adjacent the lower end thereof and being adapted to enter the vertical slots in said stiles in a manner to be guided therein, the said stiles each being provided with notches formed therein adjacent the vertical slots and communicating therewith, the said notches being arranged to receive and support said trunnions in a manner to provide fulcrums about which the respective sashes may be tilted in their respective slots, a plurality of flexible members arranged in pairs, one of each pair being secured to the vertical sides of each of the respective sashes at points sufficiently near the top end thereof to adequately support the sashes when in tilted position on said fulcrums, anti-friction rollers in each of said stiles adjacent the upper ends thereof over which said flexible members are threaded, and weights for counterbalancing said sash secured to said flexible members on the opposite sides of said anti-friction rollers from said sashes.

In testimony whereof we have signed our names to this specification, on this 2nd day of August, A. D. 1928.

ANDREW EZGETA.
CHARLES D. FLAMM.
